UNITED STATES PATENT OFFICE

2,066,424

MANUFACTURE OF SHOES

August R. Schoenky, Swampscott, Mass., assignor
to United Shoe Machinery Corporation, Paterson, N. J., a corporation of New Jersey

Application April 1, 1936, Serial No. 72,132

6 Claims. (Cl. 12—145)

This invention relates to the manufacture of shoes, and more particularly to the treatment of the marginal portions of uppers lasted over insoles. The invention is herein illustrated by reference to operations performed at the toe end of a shoe, but it is to be understood that it is not thus limited in its applicability.

In lasting the toe ends of shoes, especially when an adhesive is used to secure the uppers in lasted position, it has sometimes been the practice to fasten to the shoe over the marginal portion of the upper a retaining device for holding the upper in lasted position until the adhesive has dried or set, and thereafter to remove the retaining device from the shoe. It has also sometimes been the practice to subject the margin of the upper, immediately after it has been wiped inwardly over the insole, to heat and pressure in order to accelerate the drying or setting of the adhesive and to eliminate wrinkles in the overwiped margin. The present invention provides a method whereby are secured certain advantages of both such prior practices. In carrying out the method in the manner herein illustrated a retaining device is fastened to the shoe over the margin of the upper around the toe end of the shoe bottom while the margin is held in lasted position by toe-lasting wipers, thus insuring against any possible displacement of the upper from lasted position when the wipers are withdrawn from the shoe, and thereafter the retaining device is heated to assist in eliminating any wrinkles in the margin of the upper which it engages as well as to accelerate the drying or setting of the adhesive so that the device may be promptly removed from the shoe. As further herein illustrated, the retaining device is fastened to the shoe by tacks which penetrate through the margin of the upper and into the insole and which also are heated, so that heat is conducted by the tacks directly to the adhesive in locations immediately adjacent thereto. Further insurance is thus afforded that the upper will be held securely by the adhesive when the retaining device is removed.

The toe portion of an upper usually comprises several layers of upper materials, including a toe box and a lining, and in the practice of the method of this invention the margins of all the layers except the outer layer may, in accordance with a common procedure, be trimmed so that the overlasted margin of the outer layer will lie, at least throughout the greater portion of its width, next to the insole. As herein illustrated, however, the margins of all the layers

are lasted inwardly over the insole and the tacks penetrate through the several layers so that they conduct heat not only to portions of the adhesive lying between the different layers and between the inner layer and the insole, but also to portions of the toe box. If the toe box, therefore, is of that kind which is softened by a solvent, the heat conducted by the tacks accelerates evaporation of the solvent and the hardening of the margin of the toe box as well as the drying or setting of the adhesive applied for lasting purposes.

The invention will now be more particularly described with reference to the accompanying drawings and thereafter pointed out in the claims.

In the drawings,

Fig. 1 is a plan view of toe wipers which may be utilized to apply a retaining device to a shoe in the practice of the novel method, showing such a device mounted in recesses in the wipers;

Fig. 2 is a section on the line II—II of Fig. 1;

Fig. 3 is a vertical sectional view showing portions of a pulling-over and toe-lasting machine in which the wipers are included and which may be conveniently used in the practice of the method;

Figs. 4 and 5 are views similar to Fig. 3 illustrating different stages of the lasting operation;

Fig. 6 illustrates the heating of the upper-retaining device and the tacks after the lasting operation by means convenient for that purpose;

Fig. 7 shows the forepart of the shoe with the retaining device fastened on the toe end thereof.

The pulling-over and toe-lasting machine portions of which are shown in Figs. 3, 4 and 5 and which, as above stated, may be conveniently used in the practice of the novel method, is constructed substantially as shown and described in United States Letters Patent No. 1,980,435, granted on November 13, 1934 upon an application of C. F. and A. F. Pym. The last and shoe are supported bottom downward in the machine by a plurality of pins 2 extending through holes in the insole into sockets in the bottom of the last. The upper is pulled over the last by a plurality of grippers 4, only two of which are herein shown, and while it is held under tension by the grippers it is wiped downwardly around the toe end of the last by a toe band 6. Under the toe end of the shoe is a tack block 8 having therein a plurality of driver passages in which tack drivers 10 are movable to drive tacks upwardly into the shoe bottom. The tack block is moved upwardly to press the marginal portion of the insole

against the last, as illustrated in Fig. 3, while the upper is held under tension by the grippers, and thereafter it is moved downwardly to make way for toe-lasting wipers 12 which are moved 5 heightwise of the shoe with the toe band 6 and are advanced and closed to wipe the marginal portion of the upper inwardly over the insole, the grippers releasing the upper as these wipers begin 10 their inward wipe at the edge of the insole. In time relation to the operative movements of the wipers 12 the tack block 8 is moved upwardly and along the faces of the wipers to bring its driver 15 passages into alignment with openings 14 which extend through the wipers. Thereafter the drivers are operated to drive the tacks upwardly through these openings into the shoe bottom to fasten the overwiped margin of the upper in 20 lasted position. For a more complete understanding of the construction and operation of the machine the above-mentioned Letters Patent may be consulted.

To assist in the practice of the method of this invention the wipers 12 are provided in their top faces, near their wiping edges, with shallow 25 recesses to receive an upper-retaining device comprising two thin metal plates 16 and 18 the top faces of which are flush with the top faces of the wipers when the plates are in the recesses. The plates 16 and 18 have openings 20 arranged 30 to align centrally with the openings 14 in the wipers to receive the shanks of the driven tacks, the openings 20 being of smaller diameter than the heads of the tacks. Each plate 16 and 18 is beveled on its lower face around each of the 35 openings 20, as shown at 22 (Fig. 2), to guide the point of the tack into the opening. These bevels cause the tacks, initially tipped in the 40 driver passages as shown in Fig. 3, to assume positions substantially perpendicular to the shoe bottom, and accordingly the means disclosed in the above-mentioned Letters Patent for moving the tack block 8 lengthwise of the shoe to bring the tacks into perpendicular relation to the shoe bottom as they are being driven is preferably 45 omitted. The plate 18 has a projection 24 (Fig. 1) the edge of which is curved and fits in a complementally curved recess in the edge of the plate 16, the two plates corresponding in this respect to the shape of the wipers beneath them, 50 and one of the openings 20 is located in the projection 24 at the axis of swinging movement of the wipers 12. It will be understood that the plates 16 and 18 are carried inwardly over the insole by the wipers and have themselves a wiping 55 action on the margin of the upper, and that when the tacks are driven they fasten the plates to the shoe in pressure-applying relation to the margin of the upper, the relation of the plates and of the tacks *t* to the shoe being illustrated 60 in Fig. 7. In the return of the parts of the machine to their starting positions the wipers 12 are moved downwardly, together with the toe band 6, by the cam-operated means controlling these parts, so that the wipers clear the plates 16 and 18 before the wipers are retracted from 65 under the shoe bottom. As illustrated in Fig. 1, the upper-retaining plates do not extend the full lengths of the rows of openings 14 in the wipers, although if desired the construction may be such 70 that they will do so. If openings 14 are located beyond the ends of the plates as shown, tacks may be driven through these openings into the shoe or, as herein illustrated, such tacks may be omitted by eliminating feed of tacks to the corresponding 75 driver passages in the tack block 8.

After the toe of the shoe has been lasted as above described, the upper-retaining plates 16 and 18 and the tacks *t* are subjected to the action of heat. For this purpose there may be conveniently utilized apparatus such as shown in Fig. 6, comprising a column 26 on the top of which is a heating plate 28 having therein a curved recess 30. Projecting downwardly from the lower face of the plate 28 is a holder 32 for an electrical heating unit 34. The shoe is supported with the upper-retaining plates and the tacks against the lower face of the hot plate 28 adjacent to the recess 30 by two resilient curved rods 36 provided with a felt pad 38 for engaging the top of the toe of the shoe and holding the shoe 10 pressed up toward the plate 28. The rods 36 are supported by a holder 40 which is held on the plate 28 by set screws 42. While provision is thus made in the construction shown for treating only one shoe at a time, other shoe supports and corresponding recesses 30 in the plate 28 may be provided if desired.

It will be understood that the heat conducted through the plates 16 and 18 has a shrinking action on the marginal portion of the upper held under pressure by the plates and thus assists in eliminating any wrinkles in the upper, especially around the end of the toe, to provide a smooth seat for the outsole, and also that such heat as is conducted to the adhesive for securing the upper in lasted position serves to accelerate the drying or setting of the adhesive. The tacks extending through the upper into the insole are especially effective in conducting heat directly to the adhesive in locations immediately adjacent thereto. The shoe, therefore, may be removed from the heating apparatus after a comparatively short time, and the upper-retaining plates and the tacks may then be removed from the shoe without any danger that the upper will be displaced from lasted position.

In accordance with the procedure herein illustrated the marginal portions of a plurality of layers of upper materials, comprising a lining 44 (Fig. 3) and a toe box 46 in addition to the outer layer 48 of leather, are lasted inwardly over the insole by the wipers 12, and the tacks penetrate through all these layers and into the insole. It will be understood that prior to the toe-lasting operation an adhesive is applied to the margins of the several layers and preferably also to the margin of the insole. Rubber latex, pyroxylin cement or any other suitable adhesive, although preferably of a kind adapted to be dried or set by heat, may be used for the purpose. By conducting heat directly to portions of the adhesive between the lining and the insole and between the lining and the toe box, as well as to that between the toe box and the upper, the tacks contribute effectively to the rapid drying or setting of the adhesive located more or less remote from the plates 16 and 18. Heat also is conducted by the tacks to portions of the margin of the toe box and if the toe box is of a kind adapted to be softened by a solvent, such heat tends to 60 evaporate the solvent and thus to accelerate the hardening of the margin of the toe box as well as the setting of the adhesive.

It will be understood that the plates 16 and 18 and the corresponding recesses in the wipers 12 may be made of such dimensions that the plates will cover as much as desired of the width of the overlasted margin of the upper. If a small portion of the margin extends inwardly beyond these plates, as shown in Fig. 7, this may, if desired, be 75

trimmed flush with the portion to which heat and pressure are applied by the plates after the plates have been removed from the shoe.

Having described the invention, what I claim as new and desire to secure by Letters Patent of the United States is:

- 5 1. That improvement in methods of making shoes which consists in lasting the marginal portion of an upper inwardly over an insole, fastening an upper-retaining device to the shoe upon the marginal portion of the upper, heating said upper-retaining device, and thereafter removing said device from the shoe.
- 10 2. That improvement in methods of making shoes which consists in lasting the marginal portion of an end of an upper inwardly over an insole with an adhesive between the upper and the insole, fastening an upper-retaining device to the shoe in pressure-applying relation to the marginal portion of the upper, and thereafter heating said upper-retaining device to assist in eliminating wrinkles in the upper and to accelerate the drying or setting of the adhesive.
- 15 3. That improvement in methods of making shoes which consists in lasting the marginal portion of an upper inwardly over an insole with an adhesive between the upper and the insole, fastening an upper-retaining device upon the marginal portion of the upper by fastenings penetrating through the upper and into the insole, heating said upper-retaining device and the fastenings, and thereafter removing said device and the fastenings from the shoe.
- 20 4. That improvement in methods of making shoes which consists in lasting the marginal portions of a plurality of layers of upper materials, including a toe box adapted to be hardened by heat, inwardly over the toe end of an insole, fastening an upper-retaining device upon the marginal portion of the outer layer of the materials by fastenings penetrating through the several layers and into the insole, and heating said upper-retaining device and the fastenings to cause heat to be conducted through said device to the outer layer of the materials and through the fastenings to the marginal portion of the toe box.
- 25 5. That improvement in methods of making shoes which consists in lasting the marginal portions of a plurality of layers of upper materials inwardly over the toe end of an insole with an adhesive between the different layers and between the inner layer and the insole, fastening an upper-retaining device upon the marginal portion of the outer layer of the materials by fastenings penetrating through the several layers and into the insole, heating said upper-retaining device and the fastenings to cause heat to be conducted through said device to the outer layer of the materials and through the fastenings to the adhesive, and thereafter removing said device and the fastenings from the shoe.
- 30 6. That improvement in methods of making shoes which consists in lasting the marginal portion of the toe end of an upper inwardly over an insole with an adhesive between the upper and the insole by the use of toe wipers and also by use of said wipers applying upper-retaining plates to the marginal portion of the upper, fastening said plates to the shoe by driving tacks through the upper and into the insole while the upper is held in lasted position by the wipers, heating said plates and the tacks to cause heat to be conducted by the plates to the marginal portion of the upper and by the tacks to the adhesive, and thereafter removing said plates and the tacks from the shoe.

AUGUST R. SCHOENKY.
